UNITED STATES PATENT OFFICE

2,074,000

WALL CONSTRUCTION FOR METALLIC
BUILDINGSMark Streich, Chicago, Ill., assignor to Steel
Housing Corporation, Chicago, Ill., a corpora-
tion of Illinois

Application September 19, 1935, Serial No. 41,220

7 Claims. (Cl. 189—34)

This invention relates to wall construction for metallic buildings. Among the objects of this invention are: To provide a comparatively inexpensive metallic wall construction; to provide 5 a wall construction which effectively insulates the interior of the building against heat and cold; to provide a simple leak-proof joint for the outside sheathing thereof; to provide simple and easily assembled tying connections between- 10 the inner and outer members of the walls; to provide a simple and substantial corner construction for connecting the walls; to provide means for permitting expansion and contraction at all joints; to provide air ducts in the walls 15 of the building extending around the several sides thereof opening to the rooms and connected by flues to a furnace or air conditioner, and to simplify and otherwise improve upon the construction of comparatively inexpensive metallic buildings.

Other objects and advantages will appear in the course of the following specification, and with all of said objects and advantages in view, this invention consists in the several novel features hereinafter fully set forth and claimed.

The invention is clearly illustrated in the drawing accompanying this specification in which:

Fig. 1 is a fragmental, vertical, cross section 30 taken through the wall and floor of a metal building containing a simple embodiment of the present invention;

Fig. 2 is a horizontal section taken through one of the corner portions of the building;

Fig. 3 is a detail, fragmental, vertical section, illustrating the form of joint used between the sheets of the outside sheathing;

Fig. 4 is a fragmental, vertical section through the corner post or column taken on the line 4—4 40 of Fig. 2; and

Fig. 5 is a detail, fragmental, horizontal section through one of the joints between the outside sheathing and the corner post or column.

Referring to said drawing, which is merely 45 illustrative of one form of the invention, the reference character 10, designates the foundation wall of the building, which may be composed of concrete, brick or the like. As shown, the foundation wall may have an offset or shouldered part 11, to receive and support floor girders, one of which is shown at 12.

Extending around the top of the foundation wall is a sheet metal sill plate 13, usually composed of several sections, depending on the 50 length and breadth of the building, and said

sill plate 13 is bent along longitudinal lines to provide a top plate 14, from the outer edge of which rises an upstanding flange 15, and from the inner edge of which depends a vertical facing 16, which terminates in a horizontal flange 17, 5 that lies upon the offset part 11 of the foundation wall. The flanges 15 terminate at the corner parts of the building.

Suitably spaced along the foundation wall and rising from the sill plate are studs, one of which is seen at 18, desirably formed of sheet metal, folded and doubled upon itself to provide a T-shaped stud. Angle plates 19, spotwelded or otherwise rigidly secured to the lower ends of the studs are provided for bolting the studs to the sill plate as by bolts and nuts 41. Desirably the bolts and nuts are formed of some non-corrosive metal. The upper ends of the studs are connected by structural metal bars (not shown), thereby providing a rigid skeleton frame 20 work for supporting the outside sheathing 20, and the inner walls 44. Desirably the sheathing is composed of horizontally extending metal sheets 21, 22, placed one above the other about the building, except at the places where the 25 door and window openings occur, and novel joints 8, are provided between the adjacent sheets, which will now be described.

Referring to Fig. 3, the upper sheet 21 (of any adjacent two sheets) is folded upward as at 23, along a longitudinal line adjacent its lower edge to provide a flange 24, and then folded downward as at 25 to provide a down turned flange 26, spaced away from the flange 24 sufficiently to receive an offset flange 27, of the lower sheet 22, and the upstanding offset tongue 28, of a supporting bracket 29. It will be observed that the outer faces of the sheets 21, 22, are flush with each other. This is accomplished by offsetting inwardly the upper edge portion 27 40 of each sheet, a distance equal to the two thicknesses of metal formed by the sheet 21 above it, and its flange 24.

The brackets 29 are spotwelded or otherwise rigidly secured to the studs in position to have 45 their offset tongues 28 enter the grooves between the offset flange 27 of the lower sheet and the down turned flange 26 of the upper sheet. The brackets 29 are located on the studs at every joint between the sheets and serve to support 50 the sheets as well as to tie them to the struts and hold them flush with each other.

The lower edge portions of the bottom sheets project down somewhat below the top of the foundation wall (see Fig. 1), and have strips 55

of metal 38 spotwelded to their inner faces, that are bent down over the upstanding flanges 15 of the sill plate, thereby securely tying the lower edges of the bottom sheets to the foundation wall.

At the several corners of the building, hollow corner posts or columns 31 (see Fig 2) are provided for tying the walls together. Desirably each corner post comprises two upright metal sheets 32, 33, bent along longitudinal lines midway between their side edges as at 34 to provide the right angled outer sides 35, and the right angled inner sides 36, of a square post or column. The upright edge portions of the sheet 15 which forms the outer sides 35 are doubled upon themselves to provide flanges 37, spaced sufficiently from the sides 35, to receive outwardly bent flanges 38 that are formed on the edges of the sheet which forms the inner sides 36 (see Fig. 5). The two bent-up sheets 32, 33, are spotwelded or otherwise welded together at the joints between them, thereby providing an extremely rigid and substantial corner post. The inner sides 36 of the corner post rest on the sill plate, but the outer sides 35 project below the sill plate and overhang the upper edge portion of the foundation wall at the corner.

Angle irons 39, are spotwelded or otherwise secured to the lower edge portions of the inner sides 36 of the posts and are fastened to the foundation wall by bolts 41, that are embedded in the concrete and projected up through the sill plate 13, and through the angle irons 39, and have nuts threaded upon their upper ends which are screwed down upon the angle irons. A square flanged foot plate 40 is spotwelded to the inner faces of the post, adjacent its bottom, and rests upon the sill plate (see Fig. 4).

Flanged angle iron braces 43 are spotwelded 40 to the inner faces of the sides 35 of the post to strengthen and reinforce the post at its outer corner. These angle iron braces are suitably spaced apart along the length of the post.

The inner walls 44 of the building are desirably composed of sheets or slabs of heat non-conducting material, of which there are many kinds on the market, these employing asbestos in their composition being preferred. They are usually in the form of rectangular sheets or slabs, and for the purposes of this specification, may be termed "wall boards." The lowermost wall board designated by 45, rests in a groove formed in the top of a sheet metal base board 46. At the horizontal joints between upper and lower wall boards, they are held flush with each other by H shaped beads 47, desirably formed of strips of sheet metal bent upon themselves, as shown, to form upright flanges 48, connected by horizontal webs 49. One of the upright flanges of the bead is provided with down-turned tongues 48^a hooked upon the hereinafter described braces 50 carried by the studs. The beads carry the wall boards flush with each other and effectively tie them together and provide decorative strips running horizontally around the inner faces of the walls of the building. The beads may, of course, be continued around the partitions (not shown) as well as around the walls.

70 The wall boards are also tied to the studs 18 by other braces 50 similar to the braces 50 above referred to. All of said braces are desirably formed of strips of sheet metal folded upon themselves to provide a T shaped brace (see Fig. 2) having legs 51, that straddle and are

spotwelded or otherwise secured to the studs 18. The braces are spaced at intervals along the length of the studs and extend to the inner faces of the wall boards where the head portion 52 of each brace is slotted vertically to receive an offset down-turned tongue 53 of a bracket 54, screwed, riveted or otherwise securely fastened to the adjacent face of the wall board. In fastening a wall board 44 to the studs 18, it is lifted to bring the tongues 53 above the upper edges of the T braces 50 and then lowered, bringing the tongues down into the slots in the heads thereof. When thus fastened, the sheathing and wall boards are rigidly tied together, thus providing a very rugged, rigid and substantial wall structure.

At the corners of the building the outside sheathing and the wall boards join with the corner posts. These joints will now be described:

Spotwelded or otherwise secured to the inner sides 36 of the corner post, at spaced intervals along its length, are flanged metal strips 55, the outer flanges 56 of which are spaced from the flanges 37 of the outer sides 35 of the post, a distance equal to the thickness of the outside sheathing to receive the adjacent edges thereof. The flanged strips 55 and flanges 37 of the corner posts hold the edges of the outside sheathing firmly in place and provide for expansion and contraction thereof.

Flanges 57 disposed at right angles to each other are spotwelded or otherwise secured to the inside corner 34 of the corner post. These flanges parallel the inner flanges 56 of the flanged strips 55, and are spaced therefrom a distance equal to the thickness of the wall board and receive the end edges thereof between them, thus providing the connection between the wall boards and corner, and providing for expansion and contraction thereof. An upright corner moulding strip 58, covers the flanges 57, and provides a finish for the inside corner. The moulding strips may be secured in the wall board or to the flanges 57, by screws or otherwise.

The floor construction may be of any approved form. As shown, slabs or plates 59 containing asbestos or other thermotic insulating material, or composed of corrugated metal are laid on the foundation walls and on the girders 12. On these slabs is placed the flooring proper 60, which may be of any appropriate form. The base boards 46, are detachable and as shown are screwed to bent-up metal strips 61, that project down behind the flooring.

Hot or cold air conduits 62, may extend completely around the walls within the space between the struts 18, and the wall boards, and may be provided with outlets (not shown) at the various rooms of the building. Flues (not shown) may lead from the usual heating plant or air conditioning plant to the conduits, whereby hot air or conditioned air may be conducted through the conduits and discharged into the rooms. As is customary, a return flue may lead back to the furnace from some room of the building. Obviously, any other approved form of heating system may be employed.

To more effectively insulate the interior of the building from heat or cold all the available spaces between the outside sheathing and wall boards may be filled with mineral wool or other thermotic insulating material.

Door and window openings may be provided at any desired places, and the exposed faces

of the outside sheathing and wall boards may be painted or surface ornamented in any desirable manner. If desired, the sheathing sheets may be adjusted vertically to leave shallow grooves between adjacent sheets, which arrangement lends attractiveness to the surface decoration of the sheathing.

The building can be constructed at a considerably less cost than one of the same size made of 10 brick or wood, and provides more efficient protection against heat and cold. The parts may be fabricated at a plant preparatory to being assembled at the place where the building is to be erected.

15 More or less variation of the exact details of construction is possible without departing from the spirit of this invention; I desire, therefore, not to limit myself to the exact form of the construction shown and described, but intend, in 20 the following claims, to point out all of the invention disclosed herein.

I claim as new and desire to secure by Letters Patent:

1. In a wall construction for metallic buildings, 25 the combination of a T-shaped metallic stud, sheathing composed of joined sheets supported on said stud, T-shaped inner wall supporting braces with their webs secured to the webs of said studs and projecting inward therefrom, and 30 wall boards having brackets secured thereto and engaged with the heads of said T-shaped braces.

2. In a wall construction for metallic buildings, 35 the combination of a metallic T-shaped stud, spaced apart brackets secured to the head of the T-shaped stud and formed with offset, upstanding tongues, sheathing composed of metal sheets having joints therebetween and supported at said joints by the brackets, a T-shaped brace secured to the web of the T-shaped stud, a wall board and 40 a bracket secured to the wall board and having an offset downwardly extending tongue hooked upon the head of the T-shaped brace and supporting the wall board thereon.

3. In a wall construction for metallic buildings, 45 the combination of a folded sheet metal T-shaped stud, a folded sheet metal T-shaped brace, said brace having parallel legs straddling the web of the T-shaped stud and being secured thereto, the head of the brace having an upright slot therein, a wall board and a bracket secured thereon and formed with a down-turned offset tongue, entering the slot in the head of the 50 brace.

4. In a wall construction for metallic buildings, 55 the combination of a metallic stud, a folded sheet metal T-shaped brace secured thereto, the head of said brace having an upright slot therein, adjacent upper and lower wall boards, and H-shaped bead connecting the adjacent 60 edge portions of said wall boards, said bead be-

ing formed with a down-turned tongue at its upper edge engaging in said slot in the brace.

5. In a wall construction for metallic buildings, 5 the combination of a sill plate, metallic studs bolted thereto, outside metallic sheathing and inside wall boards carried by said studs, a sheet metal corner post bolted to said sill plate, said corner post being formed of two upright sheets, each folded along its length into right angle form, with the angles disposed opposite each other, the edge portions of one sheet being doubled upon themselves to provide flanges, and the edge portions of the other sheet being bent outward and extending into the spaces between the doubled over edge portions of the first 10 mentioned sheet, an angle shaped strip secured to the inner corner of the post and providing flanges thereon, and flanged strips secured to two sides of the post with their flanges spaced from the flanges on the post to provide grooves 15 to receive adjacent edges of the sheathing and wall boards.

6. In a wall construction for metallic buildings, 20 the combination of a corner post formed of two metal sheets, each bent to form two right angled sides, the edge portions of the two sides of one sheet being doubled upon themselves to provide grooved flanges which project beyond the two sides of the other sheet, and the edge portions of said other sheet having right angled bends forming flanges engaging in the grooves of the first mentioned flanges and rigidly secured to said flanges, flanged strips rigidly secured to the sides of the second mentioned sheet, and flanges rigidly secured to the corner of said second mentioned sheet, said flanges providing 25 spaces therebetween, outside sheathing and inside wall boards with edge portions thereof entering and held in the spaces between said flanges.

7. In a wall construction for metallic buildings, 30 a foundation wall, a sill plate thereon, a corner post joining two angularly disposed walls, said corner post being composed of two metal sheets, each bent upon itself to provide two sides, 35 the two sides of one sheet resting on the sill plate, and the two sides of the other sheet projecting down below the sill plate and overhanging the upper edge portion of the foundation wall, and the two sides of each sheet being joined at the corners to form the body of the post, angle iron plates secured to the lower ends of one of the sheets for bolting the post to the foundation wall, said post having a flanged foot plate within and secured to the lower end of the 40 post and arranged to rest on the sill plate, and horizontal flanged angle braces within the post, rigidly secured to the outer sides thereof.
